UNITED STATES PATENT OFFICE.

JAMES A. BROWN, OF PICTOU, COLORADO, ASSIGNOR OF ONE-HALF TO
GEORGE M. TOMBLING, OF PICTOU, COLORADO.

MATCH-SAFE ATTACHMENT FOR MINERS' LAMP-HOLDERS.

SPECIFICATION forming part of Letters Patent No. 709,452, dated September 16, 1902.

Application filed February 17, 1902. Serial No. 94,539. (No model.)

To all whom it may concern:

Be it known that I, JAMES A. BROWN, a citizen of the United States of America, residing at Pictou, in the county of Huerfano and State of Colorado, have invented certain new and useful Improvements in Match-Safe Attachments for Miners' Lamp-Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in match-safe attachments for miners' lamp-holders. These lamp-holders are attached to the caps worn by the miners. Matches are usually carried in the pockets of the clothing, and are therefore often spoiled by perspiration or by reason of having their igniting ends broken off.

The object of my improvement is to overcome this difficulty; and to this end the invention consists of the features hereinafter described and claimed, all of which will be fully understood by reference to the accompanying drawings, in which is illustrated an embodiment thereof.

In the drawings, Figure 1 is a perspective view of a miner's cap provided with a lamp-holder equipped with my improvements. Fig. 2 is a detail view of a lamp-holder viewed from the rear and provided with my improved match-safe. Fig. 3 is a section taken on the line $x-x$, Fig. 2.

The same reference characters indicate the same parts in all the views.

Let the numeral 5 designate the cap, and 6 the lamp-holder, consisting of a plate 6^a and upper and lower flanges 6^c and 6^d, attached to the top and the front piece or bill of the cap, respectively. The lamp 7 is held upon this holder, as shown in Fig. 1, by means of a hook 8^b. Nothing is claimed in this application on the lamp or on the general construction of the holder, since said features are old and well known.

To the inner surface of the plate 6^a of the lamp-holder is attached the match-box 8,

which is therefore located between the said plate in front and the body of the cap 5 in the rear, while it is protected from above by the flange 6^c. The body 8^a of the match box or safe is pivoted at its lower extremity to the plate 6^a by means of a suitable device passed through a lip 8^e and the said plate. This lip may be formed on or attached to the box and projects downwardly from its lower extremity. The lid or cover 8^d of the box is hinged to the body part, as shown at 8^g. Connected with this hinge-pin 8^g is one extremity of a piece of spring-wire, which is curved upwardly therefrom, as shown at 10, passes through a slot formed in the flange 6^c, and projects outwardly or laterally beyond the flange, as shown at 12, where a bend is formed. From this bend the wire is carried transversely across and above the flange 6^c, as shown at 15, to the opposite side of the latter, where it is bent or coiled around a pin 13, passed through a lug 14, attached to and projecting upwardly from the flange 6^c. From the pin 13 the wire is bent downwardly, as shown at 16, and carried transversely across the box, as shown at 17, its free extremity passing through an eye or loop 18, formed on one side of the match-box cover and at the end remote from its hinge-pin 8^g. The wire part 17 has a tendency to open the lid top or cover 8^d of the box; but this tendency is not strong enough to accomplish the purpose without assistance. However, by pushing upwardly on the projection 12 the box is turned on its pivot to the dotted-line position in Fig. 2, and the spring-arm 17 throws the lid open or to the position shown in dotted lines in the same figure and holds the lid open until the box is returned to its normal position, which may be accomplished by pushing down on the projection 12.

When the device is in use, the parts—that is to say, the lamp, the lamp-holder, and the match-box—are substantially in the relative position shown in Fig. 1. In this case the part 12 projects outwardly beyond the lamp-holder and is sufficiently extended to be easily accessible for purposes of manipulation in the manner just described.

The box is further supported on the plate 6^a of the holder by means of a metal strip 19,

forming a leaf-spring, which is attached to the inner surface of the plate at one extremity and passes through a loop formed in the adjacent surface of the box. The flange 6^d of the holder is provided with a lip 20, projecting inwardly from the said flange and extending below the bottom of the box. This feature prevents any part of the cap from moving to such a position as to interfere with the movement of the box necessary to open the lid, as heretofore described.

One side of the match-box is roughened, as shown at B, to facilitate the scratching of matches for igniting purposes.

15 Having thus described my invention, what I claim is—

1. The combination with a lamp-holder of the class described, of a match-box pivotally mounted on the inner surface of the holder and provided with a hinged lid and means connected with the lid for opening the same as the box is turned on its pivot, substantially as described.

2. The combination with a lamp-holder adapted to be attached to a cap, and having a flange projecting rearwardly from its upper extremity, of a match box or safe pivotally mounted on the holder below the flange and provided with a hinged lid, and means connected with the lid for opening the same as the box is turned on its pivot, substantially as described.

3. The combination of a lamp-holder comprising an upwardly-projecting plate having flanges projecting rearwardly from its opposite extremities, a match box or safe pivotally attached to said plate between the said flanges and having a hinged lid, and means

connected with the lid for opening the same as the box is turned on its pivot, substantially as described.

4. The combination with a lamp-holder of the class described, of a match-box pivotally mounted on the holder and provided with a hinged lid, and suitable means mounted on the lamp-holder and connected with the lid for opening the same as the box is moved on its pivot, substantially as described.

5. The combination with a lamp-holder of the class described, of a match-box pivotally mounted on the holder and provided with a hinged lid, and a device movably mounted on the lamp-holder and connected with the box and lid whereby as the said device is actuated, the box is moved on its pivot and the lid opened, substantially as described.

6. The combination with a lamp-holder of the class described, of a match-box pivotally mounted on the inner surface of the holder and provided with a hinged lid, and a wire connected at one extremity with the hinge-pin of the lid, extending outwardly beyond the lamp-holder on one side where it is bent and carried in the opposite direction a suitable distance where it is coiled around a pin on the holder, and finally bent downwardly and carried across the match-box, its free extremity being passed through a loop or eye formed on the lid, substantially as described.

In testimony whereof I affix my signature in presence of two witnesses.

JAMES A. BROWN.
